UNITED STATES PATENT OFFICE.

GROVER BLAND LEACH, OF TAMPA, FLORIDA.

KEY-POUCH.

1,187,852.

Specification of Letters Patent. Patented June 20, 1916.

Application filed January 3, 1916. Serial No. 69,881.

To all whom it may concern:

Be it known that I, GROVER BLAND LEACH, a citizen of the United States, residing at Tampa, Hillsborough county, and State of Florida, have invented and discovered certain new and useful Improvements in Key-Pouches, of which the following is a specification.

My said invention consists in an improved form of key holding wallet or pouch and in the construction and arrangement of the parts thereof, whereby such a device is provided adapted to contain the keys and key holding means in such a manner as to protect the keys from rust under the influence of moisture or perspiration thrown off by the body of the wearer, protect the pockets of the garments in which the keys are carried from undue wear, and enable the keys to be disposed in fixed relative position on the holding means, as well as to provide for their convenient and ready placing on the carrier or removal therefrom, all as will be hereinafter more fully described and claimed.

Referring to the accompanying drawing, which is made a part hereof and on which similar reference characters indicate similar parts, Figure 1 is a perspective view of a key pouch of my improved construction, the flap of the pouch being open, showing the construction of the key holding devices more clearly, Fig. 2 a side elevation of the top portion of the pouch showing the key holding means, Fig. 3 a detail cross section on the dotted line 3-3 in Fig. 2, Fig. 4 a view similar to Fig. 1, showing a modified form, and Fig. 5 a cross section on the dotted line 5-5 in Fig. 4.

40 In said drawings the portions marked A represent the pouch, B a metal bar forming the base of the key carrying device, and C the chain on which the keys are carried.

The pouch A is preferably a piece of leather, or other appropriate flexible material, doubled and adapted to be secured together at its free edges by fasteners of the type commonly referred to as "glove" fasteners, consisting of sockets 10 and 11 secured to one side, into which heads of buttons 12 and 13, secured to the other side, are adapted to be inserted.

45 The bar B is secured to the pouch A by rivets 14 and 15, and has a hook 16 formed thereon or secured thereto and extending transversely of its outer end. A latch mem-

ber 17, mounted on a pivot 18, is adapted to pass behind the top end of hook 16 at its outer end and has a detent adapted to engage in a notch formed in the adjacent edge 50 of said hook.

The outer end of member 17 is formed to extend down behind said hook and close the space between said hook and the bar B, and a projecting lug 25 is provided on the front 65 face of said member, the front edge of which is formed as a V-shaped detent and positioned to engage said notch.

The key chain C, or other appropriate flexible holder, is mounted at one end on 70 the rivet 14 and at its other end is provided with a large link 19 adapted to pass over the hook 16.

The hook 16 is so positioned in relation to the pivoted member 17 that the sharp edge 75 on the adjacent side of lug 18 will be engaged by the notch in the adjacent edge of said hook 16 and the member 17 thus held in the position shown in Fig. 1 and in whole lines in Fig. 2, in which position the link 80 19 of the chain C will be secured on said hook. Hook 16, however, is of slightly resilient material and is adapted to spring sufficiently to allow member 17 to be turned on its pivot, as indicated by dotted lines in 85 Fig. 2, when the upper end of hook 16 will be opened and the chain 19 may be readily freed therefrom for the purpose of receiving keys or permitting them to be removed therefrom. Said hook 16 has a square 90 shoulder, or off-set, 26 in its rear face near its top which serves to prevent any upward pull on the chain accidentally disengaging the latch.

In use, the outer flap of the pouch A is 95 secured to the opposite flap by means of the glove fastener devices, above described, thus completely inclosing and surrounding the keys and protecting them from the wearer as well as protecting the clothing from the 100 wear consequent upon contact with the keys.

In Figs. 4 and 5, a similar construction is shown, except that pivoted member 20 is formed with a projection 21 on its side adjacent to the bar B, which is adapted to engage with a depression in said bar, which engagement holds said member 20 in locked position. Sufficient upward pressure on 105 said member 20 will cause the parts to separate, the hook 22 yielding sufficiently to permit of this.

As will be readily seen, the arrangement shown in the modified form, as well as the arrangement shown in the principal views, provides a very convenient device for the purpose, and one which not only affords adequate protection for the keys and for the pockets in which they are carried, but also permits of an arrangement of the keys in relation to each other such as may be desired, which arrangement is preserved until purposely changed. By this means the user is enabled to soon become familiar with the position of any key on the chain or holder so that, regardless of its similarity to other keys thereon, he may readily select it in the dark or without visible observation, when desired for use. This feature adds materially to the value and convenience of the device, and the means for the ready removal and replacing of the keys, as well as for securing them against accidental displacement, all add to the advantages of the device in use.

A perforation 27 may be provided in bar B for the attachment of a chain, when desired, and it will be obvious that the form and style of the pouch may be varied to appeal to different tastes or accommodate different needs without departing from my invention as defined in the claims hereto appended. While I have shown and described the case as composed of a single piece of leather or fabric, of course, two or more pieces might be sewed together, or otherwise united, to secure similar results.

Having thus fully described my said in-

vention, what I claim as new and desire to secure by Letters Patent, is:

1. A key pouch consisting of a flexible casing with means for detachably securing its free edges together, a base bar attached thereto, a chain secured at one end to said base bar, a hook on said base bar at its other end, and a pivoted latch mounted adjacent to said hook and adapted to engage therewith by a yielding connection, substantially as set forth. 40 45

2. A key pouch comprising an inclosure case, a base bar mounted therein, a flexible member on said base bar, a hook with which 50 one end of said flexible member is adapted to engage, and a latch for retaining said flexible member on said hook, substantially as set forth.

3. A key pouch comprising an inclosing 55 case, a bar attached thereto, a flexible support attached to said bar at one end, a hook adjacent to the other end of said bar, means for mounting the other end of said flexible member on said hook, and a pivoted latch 60 for engaging said hook and retaining said flexible member thereon, substantially as set forth.

In witness whereof, I have hereunto set my hand and seal at Tampa, Florida, this 65 21st day of December, A. D. nineteen hundred and fifteen.

GROVER BLAND LEACH. [L. S.]
